[57] CLAIM

We claim the ornamental design for a global positioning system receiver enclosure, as shown.

DESCRIPTION

FIG. 1 is a left front perspective view of the global positioning system receiver enclosure comprising the present invention;

FIG. 2 is a front view thereof;

FIG. 3 is a rear view thereof;

FIG. 4 is a right side view thereof; and,

FIG. 5 is a top plan view thereof.

The broken line showing of FIG. 3 is for illustrative purposes only and forms no part of the claimed design.
